MACHINE FOR PRESSING THE BOTTOMS
OF SHOESSidney J. Finn, Beverly, Mass., assignor to
United Shoe Machinery Corporation, Paterson, N. J., a corporation of New JerseyApplication March 30, 1936, Serial No. 71,643
In Great Britain December 19, 1935

55 Claims. (Cl. 12—51)

This invention relates to machines for pressing the bottoms of shoes, and in some important aspects more particularly to machines for applying pressure and heat to the marginal portion of upper materials (hereinafter referred to inclusively as the upper) upon an insole before the outsole is applied to the shoe. The invention is herein illustrated by reference to the manufacture of shoes in which the upper is secured in lasted position around the toe end, preferably although not necessarily by adhesive, and along the sides of the forepart and shank portions by staples driven and anchored in the insole in the manner disclosed in Letters Patent of the United States No. 1,815,296, granted on July 21, 1931, upon an application of George Goddu, although it is to be understood that the invention is not limited in utility to the manufacture of shoes in which the upper is secured in lasted position by staples in both those locations.

In the manufacture of shoes in which the upper is lasted inwardly over the insole in generally parallel relation to the last bottom it has been found to be advantageous to apply pressure and heat to the overlasted margin of the upper. By the application of pressure and heat the overlasted margin of the upper is compacted closely and firmly upon the insole without any wrinkles or other surface irregularities so that the outsole when applied will lie close to that portion of the upper which is adjacent to the edge of the insole. Various features of the present invention are to be recognized in a novel organization of means for accomplishing that result. For the purpose in view, the machine herein shown is provided with a plurality of devices for applying pressure and heat to the bottoms of different shoes, each device comprising flexible resilient metal plates shaped to conform substantially to the contour of the shoe bottom lengthwise of the shoe and arranged by engagement with the overlasted margin of the upper along the opposite sides of the forepart and shank portions of the shoe bottom to position the shoe when placed initially thereon bottom downward lengthwise in the machine. The flexible shoe-engaging plates are arranged to bend and conform themselves more closely to the contour of the shoe bottom as the pressure is applied and are movable laterally of the shoe in wiping contact therewith at the opposite sides of the shoe bottom respectively in response to resistance of the shoe to the pressure applied. The flexible shoe-engaging plates of each device are reinforced by other flexible resilient metal plates which are shaped to conform to the shoe-

engaging plates and are backed up by a group of loose elements arranged to adjust themselves in accordance with the contour of the shoe and then to support the metal plates against the pressure of the shoe upon them.

In accordance with another feature of the invention, different pressing devices are so mounted that they may be moved alternately into operating position and means is provided for heating each device prior to its movement into operating position. In the construction shown, the pressing devices are mounted in pairs for turning movements about an axis extending lengthwise of the shoe so that the pressing devices of each pair may be moved successively from an inverted position into position to operate upon a shoe. Each pair of devices is supported for the pressing operation by a member which is shaped to conform substantially to the contour of the flexible shoe-engaging plates of each device and means is provided for heating the supporting member so that the shoe-engaging plates of each device are maintained in a heated condition only when each device is in its inverted position, thus insuring against applying excessive heat to the shoe. As illustrated, there is provided means which is controlled by the operator for moving the devices relatively to the heated supporting member and for rotating them about their axis to reverse their positions for operating upon different shoes.

Various features of the invention are further to be recognized in novel means for supporting the last and shoe for the pressing operation. In the construction shown, the last and shoe are supported by a shoe rest arranged to engage the forepart of the shoe, and a heel end support for engaging the top of the cone of the last. In order to hold the shoe effectively against tipping movement laterally, as pressure is applied to its bottom face, the heel end support includes a last pin arranged to engage the heel end of the last in its spindle hole. As above suggested, in the construction herein shown, each pressing device when in operating position is arranged to support a last and shoe placed initially thereon bottom downward, and in order to facilitate the placing of a last and shoe on that pressing device which is in operating position with the last pin engaging the heel end of the last in its spindle hole, the heel end support is so mounted as to permit it to be moved freely toward and from the pressing device in directions lengthwise and heightwise of the shoe and also in directions widthwise of the shoe. As herein shown, the heel end support is mounted on a holder for movements in direc-

tions widthwise of the shoe, the holder being connected to a member mounted to rock about an axis extending laterally of the shoe and on which the shoe rest is mounted for adjustment in directions lengthwise and widthwise of the shoe. These connections, in the construction shown, comprise different pairs of links which are pivotally connected to each other and to the opposite sides of the holder and the rocking member, the links thus permitting the heel end support to be moved from a shoe and last receiving position away from over the pressing devices with a last and shoe as the last and shoe are placed initially on one of the pressing devices with the 5 last pin engaging the heel end of the last in its spindle hole. In the illustrated machine, the pressing devices are moved heightwise of the shoe by power-operated means to apply pressure to its bottom face. As the pressing devices move 10 heightwise of the shoe the rocking member is rocked about its axis by engagement with the holder to move the shoe rest into engagement with the forepart of the shoe, means being provided for thereafter locking the rocking member 15 against further rocking movement in response to the pressure applied to the bottom of the shoe. In the construction shown, the above-mentioned links are held initially by spring means in a substantially straightened condition in engagement 20 with stops on the rocking member with the heel end support located in shoe-receiving position, and conveniently there is provided a flexible connection between the rocking member and the pressing devices which is arranged to hold the 25 rocking member in a substantially horizontal position, when the pressing devices are in their lowermost position in the machine, with the last pin of the heel end support substantially vertical to receive each last and shoe.

40 The above and other features of the invention, including various novel details of construction and combinations of parts, will now be more particularly described by reference to the accompanying drawings and pointed out in the claims.

45 In the drawings,

Fig. 1 is a view in front elevation of a machine in which the invention is embodied;

Fig. 2 is a view of the machine in right-hand side elevation;

50 Fig. 3 is a view partly in front elevation and partly in section on an enlarged scale of one pair of pressing or ironing devices;

Fig. 4 is a plan view of the parts shown in Fig. 3;

55 Fig. 5 is a section on the line V—V of Fig. 4;

Fig. 6 is a detail sectional view illustrating the shoe-engaging plates of one of the pressing devices as they appear in relation to a shoe pressed against them;

60 Fig. 7 is a view similar to Fig. 5 but with the parts in the positions that they assume after the shoe-engaging plates have completed their inward movements;

Fig. 8 is a vertical sectional view illustrating the mounting of the holders for the shoe-engaging plates;

65 Fig. 9 is a perspective view of a portion of the means for imparting to the shoe-engaging plates their inward movements;

70 Fig. 10 is a view in right-hand side elevation with parts broken away of means for operating the pressing devices;

Figs. 11 and 12 are detail views of the treadle 75 connections for operating the means for rotating the pressing devices;

Fig. 13 is a vertical sectional view of the heater for one pair of pressing devices;

Fig. 14 is a view partly in front elevation and partly in section of the shoe and last supporting means;

Figs. 15 and 16 are detail views of portions of the structure shown in Fig. 14; and

Fig. 17 is a perspective view of a shoe as it appears after it has been operated upon by the machine.

This invention is illustrated as applied to a machine organization which is in many respects similar to that illustrated in Letters Patent of the United States No. 1,549,243, granted August 11, 1925, on an application of E. E. Winkley, although it is to be understood that the invention is not limited to organizations of that particular character. Machines of the type illustrated in said Letters Patent are twin machines comprising two sets of mechanisms whereby one shoe is subjected to pressure simultaneously with the release from pressure of another shoe previously operated upon. Since the two sets are constructed substantially alike except that they are used to operate respectively on right and left shoes the present description will be confined, for the most part, to that set which is at the right-hand side of the machine. The machine is provided with a pair of vertical rods 20 (Figs. 1 and 2) which support adjustably near their upper ends a cross-head 22 to which there is secured a plate 24. Mounted on the plate for sliding movements in directions lengthwise of the shoe is a carrier 26 for a work support or jack which serves to support the shoe against pressure applied to its bottom face. For holding the carrier against sliding movement on the plate 24 there is provided a thumb screw 28 which extends through the carrier and is arranged to engage the plate 24. The jack comprises a shoe rest 30 for engaging the shoe or last at the top of the forepart and a heel end support 32 which engages the top of the cone of the last. In order to hold the shoe effectively against tipping movement laterally of the shoe as pressure is applied to its bottom face the heel end support 32 includes a last pin 34 arranged to extend into the spindle hole in the heel end of the last.

Mounted on the rods 20 is a slide 36 to which upward and downward movements are imparted through a link 38 connected at 40 (Figs. 1 and 10) to the slide and other mechanism not herein shown in detail since it is fully disclosed in the prior Letters Patent above mentioned. Slidably mounted on the rods 20 above the slide 36 is a casting 42 supported by a spring 44 (Fig. 10) which is arranged to yield in response to the resistance of the shoe to pressure applied. At its lower end the spring 44 engages a shoulder 46 formed within a central recess 48 in the slide 36 and at its upper end the spring engages a shoulder 50 formed within a recess in the casting 42 in vertical alignment with the central recess 48. Initially the spring 44 is under slight tension and acts to hold the casting 42 in spaced relation to the slide 36 determined by the engagement of shouldered screws 52, threaded into the slide 36, with links 54 at the lower ends of slots 56 formed in the links, the links 54 being connected at their upper ends to the casting 42 (Figs. 1 and 10). Fast to the casting 42 is a metal block 58 which serves to support shoe bottom pressing or ironing means comprising two ironing devices or units fastened together in diametrically opposed relation by end plates 60 and screws 61 and connect-

ed by trunnions 62, 64 (Fig. 3) to bars 66, 68 vertically movable in guideways formed in the slide 36. Depending from the slide 36 are spaced bearings 70 (Fig. 1) for a rockshaft 72 fast to the opposite ends of which are arms 74 and 76. The arm 74 is connected to the lower end of the bar 66 by means of a short link 78. At the opposite end of the rockshaft 72 the arm 76 is connected by means of a pivot bolt 80 to a downwardly extending link 82 and to a short link 84 pivotally connected to the lower end of the bar 68. The link 82 comprises a telescopic rod 83 and a sleeve 85 which is connected by a member 87 (Fig. 12) to a rearwardly extending arm 86 fast to a short laterally extending shaft 88 mounted in suitable bearings in the frame of the machine and having fast to it a treadle 90. Adjustably secured to the sleeve 85 is a collar 89 which is arranged to engage a collar 91 slidably mounted on the rod 83. A spring 93 surrounds the rod 83 and tends to hold the collar 91 in engagement with a pin 95 (Fig. 11) carried by the rod 83. At its upper end the spring 93 bears against a washer supported by a nut and lock-nut 97 threaded on the rod 83. The sleeve 85 and the collar 89 are slotted to receive the opposite end portions of the pin 95. Depression of the treadle 90 acts through the link 82, arms 74 and 76 and links 78 and 84 to impart upward movement to the bars 66 and 68, this movement of the bars being limited by the engagement of the link 84 with a portion of the slide 36. The treadle 90 is provided with a rearwardly extending arm 94 connected by means of a member 99 (Figs. 2 and 12) to a link 96 which is connected at its upper end to a slide 98 vertically movable in a guideway in the slide 36. The link 96 comprises a sleeve 101 fast to the member 99 and a telescopic rod 103 pivotally connected to the slide 98. A collar 105 pinned to the rod 103 is arranged to engage the upper end of the sleeve 101. Pivotally connected to the upper end of the slide 98 is an upwardly extending arm 100. Extending between a pin 102 projecting from the slide 98 and a laterally extending projection 104 on the arm 100 is a spring 106 which tends to swing the arm in a direction to hold a pin 108 carried by the arm in engagement with the upper end of the slide 98. Keyed to the trunnion 64 (Fig. 3) is a plate 110 which is held against a shoulder 112 on the trunnion by a nut and washer 114 threaded on a reduced end portion of the trunnion. Projecting from the plate 110 are four pins 116 (Figs. 2 and 3) which are located 90° apart and are spaced equal distances from the axis of the trunnion 64. The arm 100 is provided with teeth 118 which are so spaced as to engage the pins 116 successively and to rotate the plate 110 and through the trunnion 64 the ironing units in response to upward movement of the slide 98 relatively to the bars 66, 68. In order that the ironing units of each set will be moved successively into position to operate on a shoe the lateral projection 104 on the arm 110 has a plain upper surface 120 which is arranged to engage two of the projecting pins 116 when the units have been rotated through 180°. This limits the turning movement of the ironing units and also determines the relation of the ironing units to the shoe and to the supporting block 58. It will be evident from the above description that as the treadle 90 is depressed the ironing units are first moved upwardly out of engagement with the block 58 after which as the link 84 engages a portion of the slide 36 they are turned through 180° by the continued upward

movement of the slide 98 and arm 100, the spring 93 yielding in the upward movement of the slide 98 after the link 84 engages the slide 36. As the treadle is raised to lower the ironing units they are held against further turning movement by the engagement of the projection 104 on the arm 100 with two of the pins 116. It will be understood that the units will be moved upwardly far enough to prevent interference between them and the block 58 as they are rotated before the link 84 engages the slide 36.

Each ironing unit comprises a block 122 (Fig. 3) on which are mounted for movements inwardly over the bottom of the shoe a pair of flexible resilient ironing plates 124 (Fig. 4) which are shaped to conform substantially to the contour of the shoe bottom both lengthwise and widthwise of the shoe and are arranged to extend at the opposite sides of the shoe substantially from the toe end to the heel end of the shoe. Each ironing plate 124 is connected between its ends by a short link 126 (Fig. 4) to a holder 128 which is provided with slots 130 (Figs. 5, 6, 7 and 8) into which extends the outer edge portion of the plate 124, the holders being cut away, as shown particularly in Fig. 4, to permit swinging of the links 126 as the plates adjust themselves relatively to their holders in the ironing operation, as more particularly hereinafter explained, against the resistance of springs 132 which extend at the opposite ends of the plates between pins 134 carried by the plates and pins 136 projecting from the holders. Each holder 128 is provided with tail portions 138 having vertical slots 140 formed therein through which extend the shouldered portions of screws 142 (Figs. 5, 7 and 8) threaded into the block 122. The holders are forced outwardly by spring-pressed plungers 144 mounted in the block 122, the movement of the holders in this direction being limited by engagement of the holders with washers 146 on the screws 142. Overlying the plates 124 at one end is a spring clip 148 (Figs. 3 and 4) fastened to the block 122 by a screw 150 and so formed as not to extend over those portions of the plates that engage the overlaid marginal portion of the upper of a shoe at its toe end. Overlying the opposite end portion of each plate 124 is a member 152, the members 152 being so spaced as to permit the plates to engage the bottom of the shoe without interference between the heel end of the shoe and the members 152. The members 152 are fast to a member 154 which is supported by springs 156 (Fig. 2) seated in the end plate 60 and is provided with a leather pad 158 for engaging the bottom face of the heel end of the shoe. The springs 156 act to hold each member 154 in shoe-supporting position with the body portions of screws 160 threaded into the end portions of the member in engagement with uprights 162 fast to the end plate 60 at the upper ends of slots 164 formed in the uprights 162.

It will be understood that when pressure is applied to the bottom of a shoe by upward movement of the slide 36 the ironing plates 124 are flexed by the resistance of the shoe to the pressure applied to conform more closely to the contour of the shoe bottom. In order to provide for the application of more effective pressure by the plates 124 to the shoe there is arranged between each pair of plates and its associated block 122 a group of metal balls 166 (Fig. 3) filling a recess 168 in the block and being fenced in above the recess by a plurality of parallel vertical pins 75

170 which are slidingly mounted in the block 122, the pins being near enough together to prevent escape of the balls and having their upper ends normally extending above the group of balls. 5 Supported loosely on the pins 170 between their upper ends and the ironing plates 124 are thin flexible resilient plates 172 which are arranged in superposed contiguous relation and are fastened together at their opposite ends by rivets. 10 174 (Fig. 4). Extending inwardly from one edge of each of the plates 172 in parallel relation widthwise of the shoe are a plurality of slits 176 which divide the plate into a series of spring fingers 178, the slits in the different plates being 15 staggered so that the fingers of the upper plate overlie the slits in the lower plate. The plates 172 thus not only serve to reinforce the ironing plates 124 but act to prevent escape of the balls between the inner edges of the ironing plates. 20 The pins 170 are pressed against the plates 172 by springs 180 (Fig. 3) which engage enlarged heads 182 on the pins, the plates 172 being curved downwardly at their opposite ends to prevent interference between them and the springs 132. It 25 will be understood that the plates 172 are shaped to conform to the contour of the ironing plates 124 and that they are held by the spring-pressed pins 170 against the ironing plates which are supported against the upward pressure of the plates 172 at their opposite ends by the spring clip 148 and the members 152. At the opposite sides the plates 172 are arranged to underlie the holders 128 so that initially the holders of that 30 unit which is uppermost in the machine are upheld with the screws 142 engaging the holders at the lower ends of the slots 140 (Figs. 5 and 8). 35

As the ironing units move upwardly to apply pressure to the bottom of the shoe, the plates 124 and 172, in response to the resistance of the shoe 40 to the pressure applied, yield downwardly, pressing the pins 170 downwardly until the balls 166 adjust themselves in accordance with the contour of the shoe. The balls are then fixed relatively to the block 122 by the pressure against 45 them and serve as positive means to prevent any further downward yield of the plates 124 and 172 relatively to the block 122, thus rendering the plates effective to apply increased pressure to the margin of the upper. In order to insure that the balls 166 will completely fill the fenced area defined by the pins 170, the recess 168 and the plates 172, and thus apply substantially uniform 50 pressure through the plates 172 and 124 to the shoe after they become fixed relatively to the block 122, the recess 168 in the block is shaped as shown, particularly in Figs. 5 and 7, with a central substantially V-shaped rib 184 which acts to displace the balls outwardly and upwardly toward the upper ends of the pins 170 as the balls 55 adjust themselves to the contour of the shoe in response to the yielding of the plates 124 and 172.

As previously pointed out, the pressing or ironing units of each set are connected by trunnions to bars 66, 68 for turning movements about the 60 axis of the trunnions, that is, an axis extending lengthwise of the shoe and are supported for the pressing or ironing operation by the metal block 58. Preferably the block 58 of each set is shaped to conform to the contour of the ironing plates of that set and preferably also the blocks are heated to maintain the ironing plates of each inverted pressing unit in a heated condition. For heating each block 58 there are provided electrical heating units 186 which extend into the block 65 and fast to the block is a box 188 into which ex-

tend electrical conductors 190 connected with the heating units (Figs. 1 and 3).

It will be understood that when the machine is initially at rest the holders 128 and the ironing plates 124 are held in their outermost positions by the spring-pressed plungers 144. As thus positioned the ironing plates of the uppermost unit of that set which is in its lowermost position in the machine are arranged to receive and support a previously lasted shoe presented initially by the operator bottom downward by engagement with the overlaid marginal portion of the upper along the sides of the shoe substantially from the toe end to the heel end of the shoe, with the extreme rear end portion of the shoe supported by the member 154. It is contemplated that the shoe will be positioned lengthwise and laterally in the machine by the complementally shaped ironing plates 124. In order to permit the shoe to be thus positioned by the ironing plates with the heel pin 34 extending into the spindle hole in the last, the heel end support 32 is mounted for movements in directions lengthwise and heightwise of the shoe and also for movements in directions laterally of the shoe and is held initially in a position away from over the ironing units to receive each last and shoe. After a last and shoe have been mounted on the heel end support the heel end support is moved with the shoe as the shoe is placed initially on the ironing plates 124, the construction being such that the heel end support is thus freely movable with the last and shoe with the last pin 34 engaging the heel end of the last in its spindle hole. The shoe rest 30 comprises a leather covered pad 192 of rubber or other suitable material which is hollowed out laterally of the shoe and is mounted on a block 194 adjustably secured to a second block 196 mounted for sliding movements in directions lengthwise of the shoe on a rocking member 198 (Figs. 1 and 15). The member 198 is supported by the depending spaced arms 200 of the carrier 26 on a pin 202 supported by the arms and extending widthwise of the shoe. Pivotally mounted on the block 196 is a spring-controlled latch 204 arranged to engage any one of a series of recesses 206 formed in the member 198 to hold the member 196 in adjusted position lengthwise of the shoe. Formed on the block 196 is a dovetail-shaped tongue 208 extending laterally of the shoe and arranged to enter a similarly shaped groove formed in the block 194. The block 194 is held in adjusted position laterally of the shoe on the block 196 by means of set screws 210 carried by the block 194 and arranged to engage the tongue 208, lock nuts 212 being provided for holding the set screws in locking engagement with the tongue. It will be readily seen that the above construction permits the shoe rest 30 to be adjusted in directions both lengthwise and widthwise of the shoe, as required for shoes of different sizes and styles. The heel end support 32 for engaging the top of the cone of the last is freely movable in directions widthwise of the shoe along guideways formed in a holder 214, a screw 216 in the holder being provided for limiting such movement of the heel end support relatively to its holder (Fig. 16). For permitting free swinging movements of the holders 214 in directions lengthwise and heightwise of the shoe there are pivotally connected to the opposite sides of each holder equal links 218 (Fig. 2), the ends of which remote from the holder are pivotally connected to a pair of equal links 220 pivotally mounted one at each side of the member 198 on a pin 222 carried by this rocking member. Ex-

tending between the opposite end portions of the pin 222 and an upwardly extending portion 224 of the links 218 are springs 226 which tend to hold the links 218 and 220 in a substantially straightened condition with the links 220 in engagement with stops, illustrated as pins 228 projecting from the member 198, and with the holder 214 in engagement with the loop-shaped end of a rod 230 projecting from one end of the member 198.

For the convenience of the operator in mounting a shoe and last on the last pin 34, each rocking member 198 is held, when its associated ironing devices are in their lowermost position in the machine, in a substantially horizontal position with the heel pin substantially vertical by means of a chain 232. The chain 232 associated with the rocking member at the right-hand side of the machine is connected at its lower end by a spring 234 to a pin 236 projecting from the bar 68. Each chain 232 extends upwardly and over a pulley 238 mounted on the cross-head 22 and thence downwardly to one end of the pin 222. At the left-hand side of the machine the spring 234 is connected to a pin 236 projecting from the bar 68. Each chain 232 extends upwardly and over a pulley 238 mounted on the cross-head 22 and thence downwardly to one end of the pin 222. After a shoe and last have been moved by the operator into the position indicated by dotted lines in Fig. 14 with the shoe positioned properly on the ironing plates 124 of that unit which is in position to operate on the shoe, the shoe and last and the holder 214 are moved upwardly, in response to the upward movement of the slide 36, until the top of the forepart of the shoe or last engages the shoe rest 30 and the holder 214 has been moved into engagement with an abutment 240 on the rocking member 198. It will be understood that the member 198 may rock more or less about the axis of the pin 202 to move the shoe rest 30 into engagement with the shoe or last, or the abutment 240 into engagement with the holder 214, as may be necessary to accommodate lasts of different heights. For locking the member 198 thereafter against further rocking movement the upper edge portion of this member is formed as a wedge the inclined faces 242 of which are arranged to engage correspondingly inclined faces 244 formed on the carrier 26. For permitting upward movement of the member 198 into locking engagement with the carrier 26 the member 198 is provided with a slot 246 (Fig. 14) through which the pin 202 extends. Initially the pin 202 engages the rocking member 198 at the upper end of the slot 246 with the wedge-shaped upper portion of the rocking member out of engagement with the carrier. After the member 198 has completed its rocking movement to position the shoe rest 30 and the abutment 240 in engagement with the last or shoe and with the holder 214, respectively, it is moved upwardly with the last and shoe relatively to the carrier 26 until its wedge-shaped upper portion engages the inclined surfaces 244 on the carrier. Thereafter as pressure is applied to the bottom of a shoe by the ironing devices the member 198 is held against further rocking movement by the friction between the inclined surfaces 242 and 244.

It will be understood that in the upward movement of the slide 36 the last and shoe and the holder 214 are first moved into engagement with the shoe rest 30 and the abutment 240 before any substantial amount of pressure is applied to the bottom of the shoe and that in response to the pressure of the shoe upon them the plates 124 and 172 are flexed to conform more closely to the contour of the shoe bottom and yield downwardly

with the pins 170 until the balls 166 adjust themselves to the contour of the shoe and become fixed relatively to the holder 122. Thereafter in the continued upward movement of the slide 36 the pressure of the plates 124 on the overlaid marginal portion of the upper is progressively increased as the spring 44 is compressed until an abutment 248 (Fig. 10) on the slide 36 engages an abutment 250 on the casting 42, after which relatively heavy pressure is applied to the shoe through a spring 252 with which machines of the type herein shown are provided as disclosed in the above-mentioned Letters Patent. For imparting to the ironing members 124 their inward movements to iron the overlaid marginal portion of the upper there are mounted in guideways formed in the casting 42 for movements toward or from each other widthwise of the shoe slides 254 (Fig. 9). Each slide 254 is forked to straddle the rod 20 and the lower faces of the arms 256 of the forked portion of each slide are provided with rack teeth 258 arranged to be engaged by teeth 260 formed on segmental members 262 pivotally connected to the casting 42. Each segmental member 262 is connected by means of an adjustable link 264 to the slide 36. As the spring 44 begins to yield in the upward movement of the slide 36 in response to the pressure of the shoe on the ironing plates 124, the segmental members 262 are swung about their pivotal connections to the casting 42 in directions to move the slides 254 inwardly toward each other. Fast to the slides 254 are plates 266 which, as the slides 254 move toward each other, are arranged to engage the holders 128 and to move them against the resistance of the spring-pressed plungers 144 in directions to impart bodily inward movements to the ironing members 124 to iron the overlaid margin of the upper along the sides of the forepart and shank portions of the shoe. In order that the ironing members will act on the overlaid margin of the upper around the toe end of the shoe their inner edges are shaped as shown particularly in Fig. 4, those portions of the ironing members that underlie the toe end of the shoe having substantially straight inner edges and the inner edges of the members rearwardly of their toe end engaging portions being cut back more or less to permit the ironing members to adjust themselves relatively to their holders to bring their toe end portions together as they complete their inward movements.

It will be evident that by depressing the treadle 90 the ironing units of each set may be rotated when that set is in its lowermost position in the machine to bring one of them into position to operate upon the bottom of a shoe and that while that ironing unit is operating upon the shoe the ironing plates 124 of the other unit of that set are maintained in a heated condition by engagement with the heated block 58. Each set of ironing units is partially counterbalanced by torsion springs 268 which are coiled about the rockshaft 72 and tend to swing the arms 14 and 16 in directions to impart upward movement to the bars 66 and 68, thus rendering it easier for the operator to raise each set of ironing units. It will be evident also that the telescopic rods 83 and 103 may move upwardly and downwardly with the slide 36 relatively to their sleeves 85 and 101 in the power operation of the machine without imparting any swinging movements to the treadle 90.

In the operation of the machine for pressing and ironing the bottoms of shoes of the type

shown in Fig. 7 in which the marginal portion of the upper is lasted inwardly over an insole in generally parallel relation to the shoe bottom and is secured in lasted position around the toe end, 5 preferably although not necessarily by an adhesive, and along the sides of the forepart and shank portions by staples driven and anchored in the insole in the manner disclosed in Letters Patent of the United States No. 1,815,296, granted 10 on July 21, 1931, upon an application of George Goddu, the operator mounts a last and shoe on the last pin 34 at that side of the machine which is appropriate for the particular shoe whether a right or a left, the last pin being located at 15 that time in a shoe receiving position away from over the ironing units. It will be understood that the shoe rest 30 will have been properly adjusted for the size and style of shoe to be operated upon and that the ironing units will have been rotated 20 by depression of the treadle 90 to bring one of them into position to receive the shoe, the ironing plates 124 of which will have been previously heated by the block 58. After thus mounting a last and shoe upon the last pin the operator swings 25 the holder 214 toward the shoe rest 30 and also moves it heightwise of the shoe to carry the shoe bottom downward into engagement with the ironing unit and then locates the shoe both lengthwise and widthwise in the machine by the 30 complementally shaped ironing plates 124. The shoe is then in the position indicated in dotted lines in Fig. 14.

Thereafter the power operation of the machine is started by depression of a treadle 270, whereupon the ironing units, the casting 42, and the slide 36 are moved upwardly to bring the toe end of the shoe into engagement with the shoe rest 30 and the holder 214 into engagement with the abutment 240 on the rocking member 198. 35 It will be understood that the member 198 may rock more or less about the axis of the pin 202 until the toe end of the shoe and the holder 214 engage the shoe rest 30 and the abutment 240, respectively, and that by reason of the swinging 40 of the links 218 and 220 relatively to one another and to the rocking member 198 the heel end support 32 and last pin 34 will move upwardly with the last and shoe without any tendency to displace the last and shoe from adjusted position 45 on the ironing plates 124. In the continued upward movement of the slide 36, the member 198 is locked against further rocking movement by the engagement of its wedge-shaped upper portion with the inclined surfaces 244 on the carrier 50 26, after which in response to the pressure of the shoe upon them, the ironing plates 124 and the plates 172 yield downwardly, as illustrated in Fig. 7, and also conform themselves more closely to the contour of the shoe. As the plates 124 and 55 172 yield downwardly the pins 170 are pressed downwardly until the balls 166 completely fill the area defined by the plates 172, the pins 170 and the recess 168 in the block 122, and become fixed relatively to the block so as to serve as positive 60 means to transmit pressure from the block 122 to the plates. As the plates 124 of that ironing unit which is in position to operate on a shoe yield downwardly in response to the resistance of the shoe to the pressure applied, the ironing plates 65 of the other lasting unit of that set which are in engagement with the heated block 58 yield upwardly until the balls 166 of that unit become fixedly relatively to their associated block 122. 70 75 It will be evident that as the plates 124 that are

in engagement with the heated block 58 yield upwardly they conform themselves to the contour of the block so that all portions of the plates in engagement with the block are heated evenly. It will be evident also that after the balls 166 of 5 each unit become fixed relatively to their block 122 and to the plates 124 and 172 the ironing units thereafter act, substantially as rigid members through which the pressure is applied to the bottom of the shoe. 10

After the balls 166 have become fixed relatively to the block 122 with the ironing plates 124 conformed to the contour of the bottom of the shoe the pressure of the ironing plates on the overlaid marginal portion of the upper is progressively increased through the spring 44 and they are moved bodily inward as the slide 36 moves relatively to the casting 42 to compress the spring 44 and to swing the segmental members 262 in directions to move the slides 254 and plates 266 toward each other, the ironing plates 124 adjusting themselves relatively to each other and to their holders 128 to bring the inner edges of their toe engaging portions together, as shown in Fig. 7. As the ironing plates move inwardly over the shoe bottom 25 they tend to tighten the upper over the bottom face of the insole along the sides of the forepart and shank portions of the shoe as they apply progressively increasing pressure and heat to the marginal portion of the upper to iron it flat upon 30 the insole and to smooth it free from wrinkles. Thereafter the overlaid marginal portion of the upper all around the forepart, including the margin of the toe end, and along the sides of the shank is subjected to further pressure through 35 the spring 44 and the heavy toggle controlling spring 252, the pressure and heat acting to flatten the overlasted margin of the upper free from objectionable wrinkles and the heat further tending to accelerate the setting of the 40 cement at the toe end. The machine comes automatically to a stop with the shoe under pressure and while the shoe is held under pressure the operator places a last and shoe on that ironing unit which is in position to receive the shoe in 45 the other half of the machine with the last pin 34 engaging the heel end of the last in its spindle hole. As the slide 36 is thereafter lowered to release the shoe the spring 44 acts to hold the shoe pressed against the shoe rest 30 and the heel 50 end support 32, thereby preventing outward movement of the ironing plates 124 under the influence of the spring-pressed plungers 144 until the screws 52 engage the links 54 at the lower ends of the slots 56 in the links. The rocking member 55 198 is then unlocked from the carrier 26 and the ironing plates 124 are moved outwardly by the spring-pressed plungers 144. Since the shoe rests merely by its own weight on the ironing plates at this time there is no danger of displacement of the margin of the upper by the outward movement of the ironing plates 124. The operator then lifts the last and shoe off the ironing unit and removes the last and shoe from the 60 spindle 34, the springs 226 and 234 acting then 65 to hold the parts of the shoe support in their initial shoe receiving positions.

Having described the invention, what I claim as new and desire to secure by Letters Patent of the United States is:

1. In a machine for pressing the bottoms of shoes, the combination with means for supporting a shoe against pressure applied on its bottom face, of devices for applying compacting pressure along the opposite sides of the bottoms of dif- 70 75

- ferent shoes, said devices being mounted for movement alternately into operative relation to said shoe-supporting means.
2. In a machine for pressing the bottoms of 5 shoes, the combination with means for supporting a shoe against pressure applied on its bottom face, of pressing devices each arranged to receive a shoe placed initially thereon bottom downward and movable upward relatively to said 10 shoe-supporting means to apply compacting pressure along the opposite sides of the bottom of the shoe, said devices being mounted for movement alternately into operating position at the will of the operator.
- 15 3. In a machine for pressing the bottoms of shoes, the combination with means for supporting a shoe against pressure applied on its bottom face, of devices arranged to be moved successively into position to cooperate with said 20 shoe-supporting means and each constructed to apply pressure and heat to the opposite marginal portions of the bottom of a shoe, and means for limiting such movement of each device to determine its relation to said shoe-supporting 25 means.
4. In a machine for pressing the bottoms of shoes, the combination with means for supporting a shoe against pressure applied on its bottom face, of a plurality of devices each constructed to 30 apply pressure and heat to the opposite marginal portions of the bottom of a shoe, said devices being movable successively into position to cooperate with said shoe-supporting means, and means for heating said devices.
- 35 5. In a machine for pressing the bottoms of shoes, the combination with means for supporting a shoe against pressure applied on its bottom face, of a plurality of devices arranged to be moved alternately into position to cooperate with 40 said shoe-supporting means to apply pressure and heat along the opposite sides of the bottoms of different shoes, and a heater for maintaining each of said devices in a heated condition prior to its movement into position to operate on a 45 shoe.
6. In a machine for pressing the bottoms of shoes, the combination with means for supporting a shoe against pressure applied on its bottom face, of a heater, a plurality of devices each constructed to apply pressure and heat to the bottom of a shoe, said devices being mounted to swing about a common axis, and means for imparting to said devices a swinging movement of predetermined extent to bring one of them into 55 position to cooperate with said shoe-supporting means to press the bottom of a shoe and another one of them into position to be engaged by said heater.
- 60 7. In a machine for pressing the bottoms of shoes, the combination with means for supporting a shoe against pressure applied on its bottom face, of a heater, a pair of devices each constructed to apply pressure and heat to the bottom of a shoe, said devices being mounted to turn about a common axis and arranged to lie 65 normally with one of them in position to cooperate with said shoe-supporting means and the other of them in engagement with said heater, and means under the control of the operator for 70 reversing the positions of said devices.
- 75 8. In a machine for pressing the bottoms of shoes, the combination with means for supporting a shoe against pressure applied on its bottom face, of a pair of devices each constructed to apply pressure and heat to the bottom of a shoe,
- said devices being mounted in opposed relation for turning movements about a common axis and arranged to lie normally with one of them in position to cooperate with said shoe-supporting means to apply pressure to the bottom of a shoe. 5 and the other of them in an inverted position, a heater for engaging each device when it is in an inverted position, and means for reversing the positions of said devices at the will of the operator.
- 10 9. In a machine for pressing the bottoms of shoes, the combination with means for supporting a shoe against pressure applied on its bottom face, of a pair of devices each constructed to apply pressure to the opposite marginal portions 15 of the bottom of a shoe, said devices being mounted in opposed relation for movement about a common axis to bring them alternately into position to cooperate with said shoe-supporting means to press the bottom of a shoe, and means for limiting such movement of each device to determine its relation to said shoe-supporting means.
- 20 10. In a machine for pressing the bottoms of shoes, the combination with means for supporting a shoe against pressure applied on its bottom face, of devices for applying pressure and heat to the bottoms of different shoes, said devices being mounted below said shoe-supporting means to turn about an axis extending lengthwise of the shoe to permit them to be moved alternately into position to operate on a shoe. 25
- 30 11. In a machine for pressing the bottoms of shoes, the combination with means for supporting a shoe against pressure applied on its bottom face, 35 of pressing devices each arranged to engage a shoe at the opposite sides of the shoe bottom substantially from its toe end to its heel end, said devices being mounted below said shoe-supporting means to turn about an axis extending lengthwise of the shoe to permit them to be moved alternately into position to operate on a shoe, means movable by the operator for turning said devices, and means for limiting such movement of each device to determine its relation to said 40 shoe-supporting means.
- 45 12. In a machine for pressing the bottoms of shoes, the combination with means for supporting a shoe against pressure applied on its bottom face and a slide relatively movable in a direction heightwise of the shoe, of a pair of devices each arranged to receive a shoe placed initially thereon bottom downward and constructed to apply pressure and heat to the bottom of the shoe in response to relative movement of said shoe-supporting means and the slide, said devices being movable relatively to the slide about an axis extending lengthwise of the shoe, and means on said slide for engaging one of said devices to determine the relation of the other one of said devices to the shoe-supporting means. 50
- 55 13. In a machine for pressing the bottoms of shoes, the combination with shoe-supporting means and a slide relatively movable in a direction heightwise of a shoe, of a pair of pressing devices each arranged to receive a shoe placed initially thereon bottom downward and constructed to apply pressure and heat to the bottom of the shoe in response to relative movement of the shoe-supporting means and the slide, said devices being mounted for movement relatively to said shoe-supporting means about an axis extending lengthwise of the shoe, a member on said slide for engaging one of said devices to determine the relation of the other one of said devices. 60
- 65 70 75

VICES to the shoe-supporting means, and means for heating said member.

14. In a machine for pressing the bottoms of shoes, the combination with shoe-supporting means, of a slide movable toward said shoe-supporting means, a pair of pressing devices each constructed to apply pressure and heat to the bottom of a shoe, said devices being mounted to turn about an axis extending at right angles to the direction of movement of the slide, a member on the slide arranged to engage one of said devices to determine the relation of the other one of said devices to the shoe-supporting means, means for heating said member, and mechanism movable by the operator to impart turning movements to said devices to reverse their positions for operating upon different shoes.
15. In a machine for pressing the bottoms of shoes, the combination with shoe-supporting means, of a slide movable toward and from said shoe-supporting means, a pair of devices mounted for movement relatively to said shoe-supporting means about an axis extending lengthwise of a shoe and each constructed to apply pressure and heat to the bottom of a shoe, a heated member mounted on said slide and arranged by engagement with one of said devices to support them with the other one of said devices in operating position, and mechanism for rotating said devices to move them alternately into operating position at the will of the operator.
16. In a machine for pressing the bottoms of shoes, the combination with means for supporting a shoe against pressure applied on its bottom face, of a slide movable toward and from said shoe-supporting means, a pair of devices for applying pressure and heat to the bottoms of different shoes, said devices being mounted for movement relatively to said shoe-supporting means about an axis extending lengthwise of the shoe, a heated member on said slide arranged by engagement with one of said devices to support them with the other one of said devices in operating position, and treadle-operated mechanism for moving said devices out of engagement with said heated member and for rotating them about said axis to reverse their positions for operating on different shoes.
17. In a machine for pressing the bottoms of shoes, the combination with means for supporting a shoe against pressure applied on its bottom face, of a pair of devices for applying pressure and heat to the bottoms of different shoes, each of said devices comprising flexible plates shaped to conform substantially to the lengthwise curvatures of the bottom of a shoe and arranged by engagement with the shoe at the opposite sides of the shoe bottom to position the shoe relatively to said shoe-supporting means lengthwise in the machine, said devices being mounted for movements about an axis extending lengthwise of the shoe to permit them to be moved alternately into shoe-supporting position, a slide for effecting relative movement of said devices and the shoe-supporting means to apply pressure to the bottom of a shoe, and a heated member on said slide for engaging the plates of each of said devices when the other one of said devices is in shoe-supporting position, said member being shaped to conform substantially to the contour of said plates.
18. In a machine for pressing the bottoms of shoes, the combination with means for supporting a shoe against pressure applied on its bottom face, of means for applying pressure and heat to

the bottom of the shoe after lasting but before an outsole is applied to the shoe, said pressing means being mounted to turn about an axis located below the shoe-supporting means from an inverted position into a position to operate on the shoe, a heater for heating said pressing means when it is in its inverted position, a device for lifting said pressing means out of engagement with said heater, a device for turning said pressing means from an inverted position into a position to operate on the shoe, and a treadle for operating both said devices.

19. In a machine for pressing the bottoms of shoes, the combination with means for supporting a shoe against pressure applied on its bottom face, of means for applying pressure and heat to the bottom of the shoe after lasting but before an outsole is applied to the shoe, said pressing means being mounted for movement about an axis extending lengthwise of the shoe from an inverted position into a position to operate on the shoe, a heater for heating said pressing means when it is in its inverted position, a device for moving said pressing means out of engagement with said heater, a device for turning said pressing means, and a single member for operating said devices.

20. In a machine for pressing the bottoms of shoes, the combination with means for supporting a shoe against pressure applied on its bottom face, of a device constructed to apply pressure to the bottom of the shoe, said device being mounted for movement about an axis from an inverted position into position to operate on the shoe, and heating means arranged to heat said device when it is in its inverted position and away from the influence of which heating means the device is carried by its movement into operating position.

21. In a machine for pressing the bottoms of shoes, the combination with means for supporting a shoe against pressure applied on its bottom face, of a device for applying pressure and heat to the bottom of a shoe, said device being mounted for movement about an axis located below said shoe-supporting means and extending lengthwise of the shoe from an inverted position into a position to operate on the shoe, a heater arranged to heat said device when it is in its inverted position, and means for moving said device alternately into operating position and then into engagement with said heater at the will of the operator.

22. In a machine for pressing the bottoms of shoes, the combination with means for supporting a shoe against pressure applied on its bottom face, of a device for applying pressure and heat to the bottom of the shoe, said device being mounted for swinging movement from an inverted position into a position to operate on the shoe, a heater arranged to heat said device and away from which the device is carried by such movement, and means movable by the operator to effect reverse swinging movement of said device.

23. In a machine for pressing the bottoms of shoes, the combination with means for supporting a shoe against pressure applied on its bottom face, of a device for applying pressure and heat to the bottom of the shoe, said device being mounted to turn from an inverted position into a position to operate on the shoe, means movable by the operator to effect such turning movement of the device, and power means for thereafter effecting relative movement of said device and the shoe-supporting means to press the shoe.

24. In a machine for pressing the bottoms of shoes, the combination with means for supporting a shoe against pressure applied on its bottom face, of a pressing device arranged to support a shoe placed initially thereon bottom downward by engagement with the bottom of the shoe along its opposite sides substantially from its toe to its heel end, said device comprising members of flexible resilient metal conformable to the contour of the bottom of the shoe in response to pressure of the shoe upon them, a support for said flexible members movable relatively to said shoe-supporting means in a direction heightwise of the shoe, and means also conformable to the contour of the shoe for backing up said flexible members and arranged to transmit pressure positively through said flexible members to the bottom of the shoe.

25. In a machine for pressing the bottoms of shoes, the combination with means for supporting a shoe against pressure applied on its bottom face, of a pressing device arranged to support a shoe placed initially thereon bottom downward by engagement with the bottom of the shoe along its opposite sides substantially from its toe to its heel end, said device comprising members of flexible resilient metal arranged to bend and conform themselves to the contour of the shoe bottom in response to pressure of the shoe upon them, a support for said flexible members movable relatively to said shoe-supporting means in a direction heightwise of the shoe, and a group of loose elements backing-up said flexible members and arranged to adjust themselves in accordance with the contour of the shoe and then to support said flexible members against the pressure of the shoe upon them.

26. In a machine for pressing the bottoms of shoes, the combination with means for supporting a shoe against pressure applied on its bottom face, of a pressing device arranged to support a shoe placed initially thereon bottom downward by engagement with the bottom of the shoe along its opposite sides substantially from its toe to its heel-end portion, said device comprising flexible resilient plates conformable to the contour of the bottom of the shoe in response to pressure of the shoe thereon, a support for said flexible plates movable relatively to said shoe-supporting means heightwise of the shoe, a group of loose elements on said support for backing-up said flexible plates, said elements being arranged to adjust themselves to the contour of the shoe and then to support the plates against the pressure of the shoe upon them, and mechanism for moving said flexible plates inwardly in wiping engagement with the shoe bottom.

27. In a machine for pressing the bottoms of shoes, the combination with means for supporting a shoe against pressure applied on its bottom face, of a device for applying pressure and heat to the bottom of the shoe, said device comprising resilient metal plates arranged to engage the bottom of the shoe along its opposite sides, said plates being conformable to the contour of the bottom of the shoe in response to pressure of the shoe upon them, a support for said plates, a group of loose elements backing-up said plates and arranged to adjust themselves to the contour of the shoe and then to support said plates against the pressure of the shoe thereon, a slide for moving the support heightwise of the shoe, a spring extending between the support and the slide and yieldable in response to resistance of the shoe to the pressure applied, and mechanism operative in

response to the yielding of said spring for imparting to said plates movements inwardly toward each other in wiping engagement with the bottom of the shoe.

28. In a machine for pressing the bottoms of shoes, the combination with means for supporting a shoe against pressure applied on its bottom face, of a device for applying pressure and heat to the bottom of the shoe, said device comprising resilient metal plates arranged to engage the bottom of the shoe along the opposite sides of its forepart and shank portions and each flexibly conformable to the contour of the shoe in response to pressure of the shoe thereon, a support for said plates movable heightwise of the shoe, a group of metal balls arranged to adjust themselves to the contour of the shoe and thereafter to increase the pressure of said plates on the shoe, and a member yieldingly mounted on said support for engaging the bottom of the shoe at the heel end.

29. In means for pressing the bottoms of shoes, a device for pressing the bottom of a shoe after lasting but before an outsole is applied to the shoe, said device comprising flexible shoe-engaging plates arranged to engage the overlasted marginal portion of the upper along the sides of the forepart and shank portions of the shoe, said plates being flexibly conformable to the contour of the shoe and being mounted for bodily movements inwardly over the bottom of the shoe, and other plates flexibly conformable to the contour of the shoe with said first-named plates for reinforcing them.

30. In means for pressing the bottoms of shoes, a device for pressing the bottom of a shoe after lasting but before an outsole is applied to the shoe, said device comprising flexible shoe-engaging plates shaped to conform substantially to the contour of the shoe lengthwise of the shoe and mounted for movements inwardly toward each other to iron the overlasted marginal portion of the upper along the sides of the forepart and shank portions of the shoe, and other flexible plates underlying said first-named plates and each having a plurality of inwardly extending spring fingers for reinforcing said first-named plates.

31. A device for pressing the bottoms of shoes, said device comprising shoe-engaging plates arranged to engage the opposite sides of the bottom of a shoe, said plates being flexibly conformable to the contour of the bottom of the shoe in response to pressure of the shoe thereon and being mounted for movement inwardly over the bottom of the shoe, other flexible plates underlying said first-named plates and arranged to extend across the bottom of the shoe, a group of loose elements backing up said last-named plates and arranged to adjust themselves in accordance with the contour of the shoe and then to support said plates against pressure of the shoe upon them, and a fence confining said group of elements laterally and yieldable in response to the pressure of the shoe on said shoe-engaging plates.

32. A device for pressing the bottoms of shoes, said device comprising resilient shoe-engaging plates arranged to engage the opposite sides of the bottom of a shoe, said plates being flexibly conformable to the contour of the shoe in response to pressure of the shoe upon them and being mounted for movement toward each other laterally of the shoe, other resilient plates for reinforcing said shoe-engaging plates and relatively to which said shoe-engaging plates are movable laterally of the shoe, and a group of loose elements backing up said last-named plates and arranged to adjust

themselves in accordance with the contour of the shoe and then to support said plates against pressure of the shoe upon them.

33. A device for pressing the bottoms of shoes, said device comprising flexible shoe-engaging plates arranged to engage the opposite sides of the bottom of a shoe, said plates being shaped to conform substantially to the contour of the shoe lengthwise of the shoe and being mounted for movements inwardly over the bottom of the shoe in response to pressure of the shoe thereon, a group of loose elements backing up said last-named plates and arranged to adjust themselves in accordance with the contour of the shoe and then to support said plates against pressure of the shoe upon them, other flexible plates loosely mounted between said first-named plates and said group of loose elements and each having a plurality of inwardly extending spring-fingers for reinforcing said first-named plates, and a fence confining said group of elements laterally and yieldable in response to the pressure of the shoe on said shoe-engaging plates.

34. A shoe-pressing device having shoe-pressing plates arranged to engage the bottom of a shoe along the opposite sides of its forepart and shank portions, said plates being flexibly conformable to the contour of the shoe and being also mounted for movements inwardly over the bottom of the shoe in response to pressure of the shoe thereon, a group of loose elements arranged to adjust themselves to the contour of the shoe with said plates and thereafter to increase the pressure of the plates on the shoe, a fence confining said group of elements laterally and yieldable in response to the pressure of the shoe on said shoe-pressing plates, and other flexible plates loosely mounted between said first-named plates and said group of loose elements for transmitting the pressure of said loose elements to said shoe-pressing plates.

35. A device for pressing the bottoms of shoes, said device having metallic shoe-engaging plates at the opposite sides of the shoe bottom, said plates being conformable to the contour of the bottom of the shoe and being also movable inwardly over the shoe bottom, other metallic plates underlying said first-named plates and conformable to the contour of the shoe bottom with said first-named plates for reinforcing them, and means also conformable to the contour of the shoe for backing up said last-named plates and arranged to transmit pressure through said last-named plates to said shoe-engaging plates during their inward movements.

36. A device for ironing the bottoms of shoes, said device comprising flexible plates shaped to conform substantially to the contour of the bottom of a shoe lengthwise of the shoe, said plates being mounted in superposed contiguous relation and each having a plurality of inwardly extending spring fingers, and other flexible plates mounted on said first-named plates and shaped similarly thereto for engaging the overlaid marginal portion of the upper along the opposite sides of the forepart and shank portions of the shoe, said last-named plates being movable inwardly over the bottom of the shoe to iron the overlaid margin of the upper and having toe-end engaging portions provided with substantially straight inner edges arranged to contact with each other to limit their inward movements.

37. A device for pressing the bottoms of shoes, said device comprising shoe-engaging plates ar-

ranged to engage the opposite sides of the bottom of a shoe, said plates being flexibly conformable to the contour of the bottom of the shoe in response to pressure of the shoe upon them and being mounted for movement toward each other laterally of the shoe, other flexible plates for supporting said shoe-engaging plates and relatively to which the shoe-engaging plates are movable laterally of the shoe, a group of metal balls backing up said last-named plates and arranged to adjust themselves in accordance with the contour of the shoe and then to support said plates against pressure of the shoe upon them, and means acting on said balls to deflect them toward said last-named plates as they adjust themselves to insure that the pressure of said balls on the last-named plates will be substantially uniform.

38. A device for pressing the bottoms of shoes, said device comprising shoe-engaging plates arranged to engage the opposite sides of the bottom of a shoe, said plates being flexibly conformable to the contour of the bottom of the shoe in response to pressure of the shoe upon them and being movable inwardly over the bottom of the shoe, other flexible plates arranged to extend across the bottom of the shoe for reinforcing said shoe-engaging plates, a group of metal balls backing up said last-named plates and arranged to adjust themselves in accordance with the contour of the shoe and then to support said plates against pressure of the shoe upon them, and a support for said metal balls having a central substantially V-shaped rib for deflecting said balls toward said last-named plates in directions laterally of the shoe as the balls adjust themselves in accordance with the contour of the shoe.

39. A device for pressing the bottoms of shoes, said device comprising resilient shoe-engaging plates at the opposite sides of the shoe bottom arranged to bend and conform themselves to the contour of the bottom of the shoe and then to move inwardly over the shoe bottom, a support on which said plates are mounted, a group of metal balls backing up said plates and arranged to adjust themselves to the contour of the shoe in response to the bending of said plates and then to become substantially fixed relatively to one another and to the support by contact with one another and with the support, and means on said support for deflecting said balls in different directions as they adjust themselves to the contour of the shoe to insure that all portions of said shoe-engaging plates will be supported by said metal balls against further bending during their inward movements.

40. A device for ironing the bottoms of shoes, said device comprising resilient ironing plates arranged to engage the overlaid marginal portion of an upper at the opposite sides of a shoe, said plates being arranged to bend and conform themselves to the contour of the bottom of the shoe in response to pressure of the shoe upon them and then to move inwardly over the shoe bottom in response to further pressure of the shoe thereon, other resilient plates arranged to extend across the bottom of the shoe for reinforcing said ironing plates, said other plates being arranged to bend and conform themselves to the contour of the bottom of the shoe with said ironing plates, a support on which said other plates are mounted, a group of metal balls backing up said other plates and arranged to adjust themselves to the contour of the shoe in response to the bending of said other plates and then to become substantially fixed relatively to one another.

other and to said support to increase the pressure of said ironing plates on the shoe, and a substantially V-shaped rib extending lengthwise of said support for engaging and deflecting said balls outwardly toward the edge portions of said other plates as the balls adjust themselves to insure that the pressure of the balls on said other plates will be substantially uniform.

41. In a machine for pressing the bottoms of 10 shoes, the combination with means for applying pressure to the bottom of a shoe on a last, of means for supporting the last and shoe for the pressing operation comprising a shoe rest for engaging the forepart of the shoe, and a heel end 15 support including a last pin for engaging the heel end of the last in its spindle hole, said heel end support being mounted for movement in directions both lengthwise and heightwise of the shoe 20 relatively to said shoe rest into a position removed from opposite the pressing means to receive each last and shoe and then for reverse movement with the last and shoe into a position opposite said pressing means.

42. In a machine for pressing the bottoms of 25 shoes, the combination with a pressing device for engaging the bottom of a shoe on a last substantially from the toe end to the heel end of the shoe, of means for supporting the shoe and last for the pressing operation comprising a shoe 30 rest for engaging the forepart of the shoe, and a heel end support including a last pin for engaging the heel end of the last in its spindle hole, said heel end support being mounted for movement away from said shoe rest in directions 35 lengthwise and heightwise of the shoe into a shoe-receiving position away from over the heel end engaging portion of said device and then for reverse movement toward the shoe rest with the last and shoe to present the last and shoe opposite 40 site said pressing device and shoe rest.

43. In a machine for pressing the bottoms of 45 shoes, the combination with pressing means arranged to support a last and shoe placed initially thereon, of a shoe rest for engaging the forepart 50 of the shoe, and a heel-end support including a last pin for engaging the heel end of the last in its spindle hole, said heel-end support being so mounted as to permit it to be moved toward and from said pressing means in directions lengthwise and heightwise of the shoe to facilitate the placing of each last and shoe on said pressing means with the last pin engaging each last in its spindle hole.

44. In a machine for pressing the bottoms of 55 shoes, the combination with pressing means arranged to support a last and shoe placed initially thereon bottom downward, of a shoe rest for engaging the forepart of the shoe, a heel-end support including a last pin for engaging the heel end 60 of the last in its spindle hole, said heel-end support being so mounted as to permit it to be moved toward and from said pressing means in directions lengthwise and heightwise of the shoe to facilitate the placing of each last and shoe on said pressing means with the last pin engaging the heel end of each last in its spindle hole, and means for holding said heel-end support initially 65 in a location away from over said pressing means to receive each last and shoe.

70 45. In a machine for pressing the bottoms of 75 shoes, the combination with pressing means arranged to support a last and shoe placed initially thereon bottom downward, of a shoe rest arranged to engage the forepart of the shoe, a heel-end support including a last pin for engag-

ing the heel end of the last in its spindle hole, and a member on which the heel-end support is mounted for movements in directions widthwise of the pressing means, said member being mounted for movement with the heel-end support in 5 directions lengthwise and heightwise of the shoe to facilitate the placing of each last and shoe on said pressing means with the last pin engaging each last in its spindle hole.

46. In a machine for pressing the bottoms of 10 shoes, the combination with pressing means arranged to receive a shoe and last placed initially thereon, of a shoe rest for engaging the forepart of the shoe, a heel-end support including a last pin for engaging the heel end of the last in its 15 spindle hole, a member on which said shoe rest is mounted, and means connecting the heel-end support to said member for adjustment laterally of said shoe rest and for movement in directions lengthwise and heightwise of the shoe with the 20 last pin engaging the heel end of each last in its spindle hole.

47. In a machine for pressing the bottoms of 25 shoes, the combination with pressing means arranged to receive a shoe and last placed initially 30 thereon bottom downward, of a shoe rest for engaging the forepart of the shoe, a heel-end support including a last pin for engaging the heel end of the last in its spindle hole, a member on which said shoe rest is mounted and means connecting the heel-end support to said member for bodily swinging movements relatively to said shoe rest about different axes extending laterally of the shoe and for movements widthwise of the shoe to facilitate the placing of each shoe and 35 last on said pressing means with the last pin engaging the heel end of each last in its spindle hole.

48. In a machine for pressing the bottoms of 40 shoes, the combination with pressing means arranged to receive a shoe and last placed initially 45 thereon bottom downward and to move heightwise of the shoe to apply pressure to the bottom of the shoe, of means for supporting the shoe and last for the pressing operation comprising a shoe 50 rest for engaging the forepart of the shoe, and a heel-end support including a last pin for engaging the heel end of the last in its spindle hole, said heel-end support being movable relatively to said shoe rest lengthwise and widthwise of the 55 pressing means by engagement of the last with the last pin and being movable into shoe-supporting position in response to the heightwise movement of said pressing means.

49. In a machine for pressing the bottoms of 55 shoes, the combination with pressing means arranged to receive a shoe and last placed initially thereon bottom downward and to move heightwise of the shoe to apply pressure to the bottom of the shoe, of means for supporting the shoe and last for the pressing operation comprising a shoe 60 rest for engaging the forepart of the shoe, a heel-end support including a last pin for engaging the heel end of the last in its spindle hole, said heel-end support being adjustable relatively to said shoe 65 rest lengthwise and widthwise of the pressing means by engagement of the last with the last pin and being movable with the last and shoe in the heightwise movement of said pressing means, and means for moving the shoe rest into engagement with the forepart of the shoe by the movement of the heel-end support heightwise of the shoe.

50. In a machine for pressing the bottoms of 70 shoes, the combination with pressing means ar- 75

- ranged to receive a shoe and last placed initially thereon bottom downward, said pressing means being movable heightwise of the shoe in the pressing operation, of a shoe rest for engaging the forepart of the shoe, a heel-end support including a heel pin for engaging the heel end of the last in its spindle hole, a member on which said shoe rest is mounted for adjustment in directions lengthwise and widthwise of the shoe, and means 5 connecting the heel-end support to said member for movement in directions lengthwise and heightwise of the shoe to facilitate the mounting of each last and shoe on said pressing means with the heel pin engaging the heel end of each last 10 in its spindle hole and for movement into engagement with said member in the heightwise movement of said pressing means.
51. In a machine for pressing the bottoms of shoes, the combination with pressing means arranged to receive a shoe and last placed initially thereon bottom downward and to move heightwise of the shoe to apply pressure to its bottom face, of a last pin for engaging the heel end of the last in its spindle hole, a holder carrying said 15 last pin and so mounted as to permit it to be swung in directions lengthwise of the shoe and to be moved in directions heightwise and widthwise of the shoe to facilitate the placing of each last and shoe on the pressing means with the last 20 pin engaging each last in its spindle hole, a member for engaging said holder in the heightwise movement of said pressing means, said member being mounted to swing about an axis extending laterally of the shoe, and a toe rest on said member 25 arranged to be moved into engagement with the forepart of the shoe on said pressing means in response to such swinging movement.
52. In a machine for pressing the bottoms of shoes, the combination with pressing means arranged to receive a shoe and last placed initially thereon bottom downward and to move heightwise of the shoe to apply pressure to its bottom face, of a last pin for engaging the heel end of the last in its spindle hole, a holder carrying said 30 last pin and so mounted as to permit it to be moved in directions lengthwise and heightwise of the shoe to facilitate the placing of each last and shoe on the pressing means with the last pin engaging each last in its spindle hole, a member for engaging said holder in the heightwise movement of said pressing means, said member being mounted to swing about an axis extending laterally of the shoe, a toe rest on said member 35 for engaging the forepart of the shoe on said pressing means in response to such swinging movement, and means for locking said member against further swinging movement as pressure is applied to the bottom of the shoe by said pressing means.
53. In a machine for pressing the bottoms of shoes, the combination with pressing means ar-

ranged to support a last and shoe placed initially thereon bottom downward, of a shoe rest for engaging the forepart of the shoe, a heel-end support including a last pin for engaging the heel end of the last in its spindle hole, a member on which said shoe rest is mounted, a holder for said heel-end support, and connections between the holder and said member arranged to permit movement of said heel-end support relatively to said shoe rest in directions lengthwise and heightwise of the shoe with each last and shoe as they are placed initially on the pressing means, said connections comprising links pivotally connected to said holder, and other links pivotally connected to said first-named links and to said member. 15

54. In a machine for pressing the bottoms of shoes, the combination with pressing means arranged to support a last and shoe placed initially thereon bottom downward, of a shoe rest, a heel-end support including a last pin for engaging the heel end of the last in its spindle hole, a member on which said shoe rest is mounted, a holder for said heel-end support, connections between the holder and said member arranged to permit movement of said heel-end support relatively to said shoe rest in directions lengthwise and heightwise of the shoe, said connections comprising links pivotally connected to said holder, other links pivotally connected to said first-named links and to said member, spring means tending normally to swing said links into a straightened condition, and means for limiting such swinging movements of the links with the last pin of the heel-end support in a substantially vertical position. 35

55. In a machine for pressing the bottoms of shoes, the combination with pressing means arranged to support a last and shoe placed initially thereon bottom downward, of a shoe rest arranged to engage the forepart of the shoe, a 40 rocking member on which said shoe rest is mounted, a heel-end support including a last pin for engaging the heel end of the last in its spindle hole, a holder for said heel-end support, connections between the holder and said rocking member comprising different pairs of links pivotally connected to the opposite sides of the holder and said rocking member, the links of each pair being also pivotally connected to each other, spring means tending to swing said links into a substantially straightened condition, a pair of stops for limiting such swinging movement of the links with the heel-end support in a shoe and last receiving position away from over the pressing means, and a flexible connection between the pressing means and said rocking member arranged to hold said rocking member normally in a substantially horizontal position with the last pin of said heel-end support substantially vertical. 50

SIDNEY J. FINN.
